UNITED STATES PATENT OFFICE.

RICHARD LESTER WILCOX, OF WATERBURY, CONNECTICUT, ASSIGNOR TO THE
WATERBURY FARREL FOUNDRY AND MACHINE COMPANY, OF WATERBURY,
CONNECTICUT, A CORPORATION OF CONNECTICUT.

FEED MECHANISM.

1,309,749.

Specification of Letters Patent. Patented July 15, 1919.

Original application filed May 28, 1915, Serial No. 31,019. Divided and this application filed May 8, 1917.
Serial No. 167,245.

To all whom it may concern:

Be it known that I, RICHARD LESTER WILCOX, a citizen of the United States, residing at Waterbury, in the county of New Haven and State of Connecticut, have invented certain new and useful Improvements in Feed Mechanism, of which the following is a specification, reference being had therein to the accompanying drawings.

The invention herein described, being a division of the application filed May 28, 1915, Serial Number 31,019, patented January 15, 1918, Number 1,253,322, relates particularly to feed mechanism, and more especially to such feed mechanism as is designed to automatically and intermittently feed wire to the dies of a heading machine, although not limited thereto.

It is the object of the invention, among other things, to provide means, whereby the feed mechanism will feed wire into the heading dies only at such times as the heading dies are in a position to receive them; to provide means for assuring a full length feed; and in conjunction therewith, to provide readily accessible mechanism that may be easily controlled, which will stop the feed when desired and necessary.

To these and other ends, my invention consists in the feed mechanism, having certain details of construction and combinations of parts, as will be hereinafter described and more particularly pointed out in the claims.

Referring to the drawings, in which like numerals of reference designate like parts in the several figures;

Figure 1 is a side elevation of a portion of a header having my improved mechanism connected therewith;

Fig. 2 is a fragmentary plan view of one end thereof;

Fig. 3 is an enlarged sectional view of the parts, taken upon line 3-3 of Fig. 2;

Fig. 4 is an enlarged sectional view of the parts taken upon line 4-4 of Fig. 3;

Fig. 5 is an enlarged sectional view of the parts taken upon line 5-5 of Fig. 3;

Fig. 6 is a detail view of the link block adjusting mechanism; and Fig. 7 is a detail view of the latch and trip mechanism.

The feed mechanism as shown and described herein is constructed without a pawl

and ratchet, friction devices being substituted therefor, and elements movable in the path of said friction devices are provided to release their grip and stop the feed. This latter feature is controlled from a handle that is mounted upon a fixed part, its position thereby being always substantially the same and materially enhancing the convenience of its operation as distinguished from the type of pawl mechanisms above referred to, wherein the pawl usually moves about the axis of the pawl disk and must be grasped while in motion. In the latter form it is apparent that the more rapid the feed, the more difficult it is to grasp and operate the continually moving pawl.

The handle aforesaid, employed for checking the feed mechanism, can only be manipulated at a predetermined time or times, of which the open position of the dies relatively to the feed passage is the determining factor, because of an interlocking action of a device which is actuated directly by said dies independently of means and mechanism, not shown, which establish operative timed relation between the continuously operating dies and the intermittently operated feed mechanism. Said handle may be manipulated so as to release or stop the feeding operation at predetermined times when permissible, and when held in an open position, permits the feed mechanism to be operated at regular intervals in timed relation to said dies.

The length of the stroke of the feed mechanism is adjustable, means being provided for accomplishing this through a coarse adjustment and a fine adjustment, either one or both of which may be dispensed with if desired.

In the drawings the numeral 1 designates the body of the machine supported upon legs 2 and 3 is the fly wheel.

Journalized in the body 1 is a shaft 4, which derives a rocking movement through a shifter arm 5, by means not constituting any portion of the present invention.

All of the parts just described are common and well known in the art and require no additional description or illustration herein.

The dies are designated by the numeral

6 and have a lateral movement within the body 1 through the reciprocating action of the plate 7 by means not herein shown or described, and travel so that the grooves in 5 the meeting faces thereof pass from the line of the wire feed, designated 8, to the line of the heading operation, designated by the numeral 9. The dies are held against the plate 7 and returned to the line 8 by mechanism 10 comprising the plate 10 connected to the ends of the slidably mounted rods 11, having a trip head 12 thereon, against which is the end of a spring 13 secured at its opposite end to the body 1 by a cap 14. A 15 screw 15 threaded through the head 12 and abutting against the body 1, limits the inward movement of the parts just described.

Pivottally secured within the stud 16 is the trip latch 17 having trip arms 18 and 19 20 thereon, through the latter of which is an adjusting screw 20 that lies within the path of movement of the head 12. This latch is subject to the pressure of a spring 21 that bears against the end of a pin 22 contacting 25 with the arm 18 and actuates the said latch to move the trip arm 18 away from the body 1.

Connected with the body 1 is a roll frame 23, within which are rotatably mounted the 30 shafts 24 and 25, each of which is provided with a feed roll 26 and intermeshing gears 27 and 28. In one face of the gear 28 is a ring 29 and concentric therewith is a clutch plate 30 secured by screws 31, and having a 35 plurality of notches 32 in the edge thereof, said notches having roll faces 33 and an end face 34. Within each of said notches is a roll 35 that is moved in one direction between the face 33 and the inner face of the 40 ring 29 by a pin 36 having a head 37 thereon with an angular face which contacts with the roll 35. A spring 38 pressing against the end of the pin 36 provides a yielding pressure against the roll 35.

45 Rotatably mounted upon the roll shaft 25 is a trip head 39 having the offset arm 40 integral therewith, within which is mounted the block 41 that is adjustable through a screw 42 threaded therein and rotatable 50 within the trip head 39 with a spiral gear 43 thereon which meshes into a spiral gear 44 fixed upon a shaft 45 rotatable in the trip head 39 through a knob 46 fixed upon the outer end thereof. The position of the knob 55 46 is so relatively close to the center of the shaft 25 that its circular movement is very limited and it may be readily rotated during the movement of the trip head 39 to vary the radial position of the block 41 within the 60 arm 40. A link 47 that connects the shifter arm 5 and block 41 is secured to the latter by a pin 49 and to the former by a pin 50, which is held against accidental disengagement by a catch plate 51 rotatably secured 65 to the link by a screw 52 and which enters

an annular groove 53 in the pin 50. This catch plate and its method of operation constitute no part of my present invention.

The length of stroke of the link 47 is varied by shifting the point of connection 70 thereof with the shifter arm 5, this being accomplished by passing the pin 50 through any one of a plurality of holes 54 in the said shifter arm. This adjustment is generally known as a coarse adjustment. The fine adjustment 75 of the feed is determined by the radial position of the block 41 within the offset arm 40, which, as above described, is secured by rotation of the knob 46.

As the shifter arm 5 moves to the left, as 80 shown in Fig. 1, the trip head 39 is moved in an anti-clockwise direction, at which time the clutch plate 30 (which is fastened to the trip head 39) moves the rolls 35 against the faces 33, assisted by the action of the pins 85 36 so that the rolls impinge against the inner surface of the ring 29, causing a frictional engagement between all of the parts. The ring 29 will now rotate, and through it, the gear 28, with which it is connected, which 90 rotation in turn is transmitted to the gear 27, shafts 25 and 24 to the rolls 26, causing the same to impart an endwise feed movement to the wire therebetween.

Upon the reverse movement of the shifter 95 arm 5, the trip head 39 is moved in the opposite direction, and the clutch plate 30, having faces 33, contacts with the periphery of each of the rolls 35 and moves them against the heads 37, and the tension of the 100 spring 38. The effect of this action is to break the connection therewith so that the trip arm rotates freely without imparting movement to the feed mechanism.

Immediately upon the movement of the 105 shifter arm 5 being reversed from that last described, the friction hold of the rolls 35 between the clutch plate 30 and the ring 29 takes place, and all of the parts move with the motion of the trip head 39.

The mechanism for stopping the feed operation comprises a disk 48, which is rotatably mounted upon the trip head 39, with one face thereof against the face of the ring 29 (see Fig. 4), and inclosed within an overhanging lip 55 upon the gear 28. Fixed 110 within this ring are a plurality of release pins 56, corresponding in number with the rolls 35, and projecting into the path of movement thereof and lying between the 115 roll face 33 and the ring 29. The center of these release pins 56 is more distant from the center of the shaft 25 than that of the rolls 35, so that as they engage the said rolls they have a tendency to force the same against 120 the face 33 and away from the inside of the ring 29.

Rotatably mounted upon a stud 57 fixed in the trip head 39, is a release arm 58 that is connected with the disk 48 through the pin 130

59, and having a roll 60 rotatably mounted upon one end thereof. A spring 61 connected at one end to a pin 62 in the outer end of the offset arm 40, and at the other end to the pin 59, always exerts its tension so as to rock the release arm 58 upon its pivot mounting and move the disk 48 upon its axis and force the release pins 56 into contact with the rolls 35.

10 Pivottally secured to the body 1 upon the stud 63, is a roll arm 64, which is connected with the handle 65 by the link 66. The handle 65 is provided with a tail piece 67, and is rotatably mounted upon a fixed stud 15 68. In Figs. 1 and 3 the roll arm 64 is shown in such position that the curved portion or sweep thereof is concentric with the axis of the shaft 25, in which position the roll 60 rides against its inner face, being 20 held there by the spring 61. While the parts are in these relative positions the disk 48 moves with the trip head 39 as a unit, and the release pins 56 and rolls 35 occupy the relative positions substantially as shown 25 in Fig. 3.

To move the rolls 35 so as to prevent them having a frictional engagement with the clutch plate 30 and ring 29, the handle 65 is moved upon its pivot mounting to the position shown by broken lines in Figs. 1 and 3, which brings the roll arm 64 to the position shown by broken lines in Figs. 1 and 3, wherein the curved position or sweep thereof is eccentric to the axis of the shaft 25.

30 35 The spring 61 still maintains the roll 60 in contact therewith, but while moving to this latter position, the release arm 58 is moved upon its pivot mounting and an independent movement is given to the disk 48 through the pin 59 and the release pins 56 are moved against the rolls 35, which shift and break their frictional engagement between the clutch face 33 and the ring 29. So long as the roll arm 64 occupies the last described position, the shafts 25 and 24 remain stationary and no feed movement is transmitted to the rolls 26.

When the handle 65 is in the position shown by full lines in Fig. 1 the feed mechanism is operating, and the trip latch 17 is in the position shown by broken lines in Figs. 2 and 7, at which time the tail piece 67 is in front of the trip arm 18, as shown by full lines in said Fig. 1, and by broken lines in Fig. 7, and the screw 20 in the end of said latch is out of the path of movement of the head bracket 12, and the trip arm 18 in this position is held against the tail piece 67 by the spring pressed pin 22. It is therefore impossible to discontinue the feed operation when the parts are in the position just described, because the tail piece 67 in its then position prevents movement of the trip arm 18 and stop screw 20.

65 When the handle 65 is moved to the posi-

tion shown by dotted lines in Fig. 1, the non-feed position against the stop pin 69, the tail piece 67 has moved away from the front of the trip arm 18, as before described, to a position where it is opposite 70 the notch 70 in the outer end of said trip arm 18, which is then moved by the spring pressed pin 22 to the position shown by full lines in Figs. 2 and 7, wherein the tail piece 67 is engaged in the notch 70 and remains 75 engaged until the head 12 strikes the screw 20, whereby the latch is thrown to the broken line position shown in Fig. 7. During the retention of the tail piece 67 by the notch 70 said handle 65 is effectually held against 80 further movement to its full line position until the trip latch 17 is released by the next movement of the head bracket 12, through the action of the dies, which engages the end of the screw 20 and rocks the trip latch 85 and moves the same out of the path of the tail piece 67. The handle 65 can now be operated again if desired, as above described, so as to permit reestablishment of the feeding operation by shifting the handle to the 90 operative position if said handle had been shifted to the inoperative position in the interval.

In Fig. 2 of the drawing the dies are shown in position for feeding the wire, and 95 the head bracket 12 in its inward position with the trip arm 18 in a position to prevent the operator from throwing in the feed lever 65. In other words, locking the lever 65 to prevent the operator from throwing in the feed, due to the trip arm 13 holding the tail piece 67. This prevents the interruption of the feed of wire of predetermined lengths, and thus insures against a short feed, that is, one that does not advance the wire to the 100 predetermined length. When the dies move and shear off the wire and are over to the heading line 9, the head bracket 12 is in its outward position and the trip arm 18 would then be in a position shown by dotted lines 105 in said figure, at which time the feed lever 65 would be free to be moved to the full line position in Fig. 1, as the trip arm 18 would be swung out of the path of movement of the tail piece 67 on the feed lever 65. In 110 other words, the correct time for throwing in the feed is when the dies are in the heading position. At this time the feed arm 40 is returning, and at any interval of time while the feed arm 40 is returning is the proper 115 time for the feed lever 65 to be thrown into feeding position. Before the feed arm 40 receives its forward motion for feeding the wire, the dies are pushed over the line 8 to receive the wire and at the same time allowing the trip arm 18 to lock the feed lever 65 so that the operator cannot throw in the feed to get a partial, or short, feed.

120 It will be observed, that with this device, instead of the operator attempting to catch a 130

fast moving handle to throw the feed in or out, as is the case with the ratchet and pawl mechanism in common use, it is only necessary for him to grasp a conveniently located stationary handle that is always in the same relative position. The handle 65 can be moved from its full line (feed) position to its dotted line (non-feed) position in Fig. 1, at any time, irrespective and regardless of any other part. The operator, however, is not at liberty to reverse these operations by throwing the handle 65 into a position that will allow a feed of the wire until the correct time, this being determined by the position of the trip latch 17, which in turn is controlled by the position of the dies. When the handle 65 is in the feed position (full lines, Fig. 1), it cannot be moved farther to the right, as the square end 71 of the link 66 abuts against the end face of the slot in the said handle, (see Fig. 3) and the center of the pin 72 is slightly beyond the dead center sufficiently to hold it in position and resist any strain upon the roll arm 64 by the contact of the roll 60 thereon. Normally the handle 65 is in such position as to permit successive feeding movements and is only actuated when it is desired to discontinue the feed for any purpose.

30 There are minor changes and alterations that can be made within my invention, and I would therefore have it understood, that I do not limit myself to the exact construction herein shown and described, but claim all that falls fairly within the spirit and scope of the appended claims.

Having described my invention, what I claim as new, and desire to secure by Letters Patent, is:

- 40 1. In a feed mechanism, the combination with companion rotary shafts; of an operative connection therebetween; means for intermittently rotating said shafts, comprising a notched element; a member covering the 45 notch in said notched element; an independent member within said notch mounted so that in one position it contacts with one face of the notch and one face of the said member covering the notch; means for imparting an intermittent rotary movement to said notched element; a trip member in the path of said independent member; means for mounting said trip member so that it may move with or independently of said notched 55 element, said means comprising a rock arm; a roll arm having a curved face thereon; means for moving said roll arm so that said curved face may be either concentric or eccentric with the axis of said notched element, 60 said means comprising a handle pivotally mounted upon a fixed part; a connection between said handle and said roll arm, said connection being such that when said roll arm is moved into a position where- 65 in the curved face thereon is substantially

concentric with the axis of said notched element, the same will be either on or slightly beyond a dead center, thereby locking the same and preventing the premature accidental movement thereof; means controlled by the action of the heading dies to prevent movement of said handle except at predetermined periods, said means comprising a pivotally mounted trip member; an adjustable member therein in a path of movement of a die controlled element and another arm in the path of said handle; and means for holding said rock arm against said curved face when the same is in its concentric position whereby the said independent member will move as a unit with said notched element.

2. In a feed mechanism, the combination with companion rotary shafts; of an operative connection therebetween; means for intermittently rotating said shafts, comprising a notched element; a member covering the notch in said notched element; an independent member within said notch mounted so that in one position it contacts with one face of the notch and the member covering the notch; means for imparting an intermittent rotary movement to said notched element; a trip member in the path of said independent member; and means, controlled by the action of the heading dies to determine the time of operation of said means for intermittently rotating said shafts.

3. In a device of the character described, the combination with movable dies; of a mechanism for feeding material to said dies; means for operating the same intermittently; feed controlling means; and means comprising a trip latch released by a trip head receiving motion direct from the dies, whereby said feed controlling means is locked in predetermined positions of said dies.

4. In a device of the character described, the combination with movable dies; of a mechanism for feeding material to said dies; means comprising a clutch device for operating the same intermittently; controlling means for opening and closing said clutch device; and means for locking said controlling means against movement until the dies are in a predetermined position.

5. In a device of the character described, the combination with movable dies; of a mechanism for feeding material to said dies; manually controlled means for operating the same intermittently; and mechanism between said dies and said manually controlled means, comprising a self-locking latch disengaged by a trip head and actuated by said dies when in one of its positions, to permit movement of the latter means.

6. In a device of the character described, the combination with movable dies; of a mechanism for feeding material to said dies

comprising a clutch operative in one direction of rotation only; means for operating the said mechanism intermittently; an operating lever mounted upon a fixed part for controlling the movement of said latter means; a self-locking device for said operating lever; and means actuated by said dies, when in a predetermined position for unlocking said operating lever.

7. In a device of the character described, the combination with movable dies, of a mechanism for feeding material to said dies, said mechanism comprising a rock shaft, means for rocking the same, and a feed roll and clutch mounted on said shaft; a member mounted upon a fixed part; an operative connection between said member and feeding mechanism whereby the same may be caused to operate intermittently; and mechanism between said dies and said member to prevent the movement of the latter except when they are in the proper relative positions, said mechanism being subject to the action of said dies.

8. In a device of the character described, the combination with movable dies; of a mechanism for feeding material to said dies, operating through a clutch engaged in one direction of travel only; a member mounted upon a fixed part; an operative connection comprising a link, an arm, and a clutch tripping device, between said member and the feeding mechanism, whereby the same may be caused to operate intermittently; and mechanism between said dies and said member, comprising a latch and releasing device, to prevent movement of said member except when the latch and releasing device are in the proper relative positions, the then position of the mechanism being determined by the position of said dies.

9. In combination with movable heading dies, a mechanism for feeding material thereto; feed controlling means and a locking device therefor; and means, the action of which is determined by the movement of said dies, whereby said locking device is maintained in an engaged position to prevent the feeding of material to said dies except when said dies are in a position to receive said material.

10. A feed mechanism of the class described, comprising a power transmitting member; a feed roll; a shaft therefor; a clutch mounted on said shaft; means for freeing the clutch in one direction of travel, whereby intermittent rotation of said feed roll is effected in one direction only; a feed checking means; and locking means for preventing operations of the feed checking means at predetermined times.

11. A feed mechanism of the class described, comprising a power transmitting member; a feed roll; a shaft therefor; a clutch mounted on said shaft; means for

freeing the clutch in one direction of travel, whereby intermittent rotation of said feed roll is effected in one direction only; controlling means for said clutch freeing means; and locking means for rendering 70 said controlling means inoperable at predetermined times.

12. In a feed mechanism of the class described, the combination of power transmission mechanism; a connecting member 75 therefor; a feed roll; a shaft therefor; a clutch mounted on said shaft; means for freeing the clutch in one direction of travel, whereby intermittent rotation of said feed roll is effected in one direction only; adjusting means to vary the position of said connecting member; mechanism whereby regulation of the feed is obtained; a feed checking means and locking means for preventing 80 operation of the feed checking means 85 at predetermined times.

13. In a feed mechanism of the class described, the combination with a power transmitting member; of a shaft; a feed roll and a clutch mounted on said shaft; means for 90 freeing the clutch in one direction of rotation, whereby said feed roll is rotated in one direction only; controlling means for said clutch freeing means; locking means for rendering said controlling means inoperable at predetermined times; and adjusting means applied to a connecting member 95 for said power transmitting member, whereby regulation of the feed is obtained.

14. In a feed mechanism of the class described, the combination with movable dies; of feed rolls mounted on separate shafts; a rocking member mounted on one of said shafts; power transmission means connected to said rocking member for intermittently 100 operating said feed roll; a clutch device mounted on the same shaft as said rocking member; automatic means for engaging said clutch in one direction of rotation only; manually operatable controlling means for 105 said engaging means; and locking means for preventing operation of said controlling means when said movable dies are in predetermined positions.

15. In a feed mechanism of the class described, the combination with movable dies; of feed rolls mounted on separate shafts; a rocking member mounted on one of said shafts; power transmission means connected to said rocking member for intermittently 110 operating said feed roll; a clutch device mounted on the same shaft as said rocking member; automatic means for engaging said clutch in one direction of rotation only; manually operatable controlling means for 115 said engaging means; locking means for preventing operation of said controlling means when said movable dies are in predetermined positions; and a lock actuating device operated directly by said movable dies. 120 125 130

16. In a feed mechanism of the class described, the combination with movable dies; of feed rolls mounted on separate shafts; a rocking member mounted on one of said shafts; power transmission means connected to said rocking member for intermittently operating said feed roll; a clutch device mounted on the same shaft as said rocking member; automatic means for engaging said clutch in one direction of rotation only; manually operable controlling means for said engaging means; locking means for preventing operation of said controlling means when said movable dies are in predetermined positions; a lock actuating device operated directly by said movable dies; and means for timing the action of said lock actuating device.

17. In a feed mechanism of the class described, the combination with movable dies; of feed rolls mounted on separate shafts; a rocking member mounted on one of said shafts; power transmission means connected to said rocking member for intermittently operating said feed roll; a clutch device mounted on the same shaft as said rocking member; automatic means for engaging said clutch in one direction of rotation only; manually operable controlling means for said engaging means; locking means for preventing operation of said controlling means when said movable dies are in predetermined positions; a lock actuating device operated directly by said movable dies; means for timing the action of said lock actuating device; and feed regulating means carried by said rocking member.

18. In a feeding mechanism of the class described, the combination with a feed roll driven through a clutch operative in one direction only; a tripping device operated by a tension device for freeing said clutch; and controlling means for said tension device, comprising an operating lever; and a movable member link connected thereto, said movable member bearing on a free end of said tension device and maintaining said trip device in an engaged position against the tension device which releases said tripping device.

19. In a feeding mechanism of the class described, the combination with a feed roll driven through a clutch operative in one direction of rotation only; of a clutch tripping device rotative co-axially with said clutch; a tension releasing device for said tripping device; a member overcoming said releasing device and preventing its action; and operating and controlling means for said member.

20. In a machine having a feed mechanism, the combination of a feed roll, intermittently driven through a clutch operative in one direction of rotation only; a clutch tripping device rotating with said clutch; a

tension releasing device for said tripping device; a movable member overcoming said releasing device and preventing its action; operating and controlling means for said movable member; and means for locking said operating and controlling means at predetermined times of which the relative position of the working elements of the machine is the determining factor.

21. In a feed mechanism of the class described; an oscillating power member; an arm to which motion is imparted by said power member; a rock shaft for said arm; a fixed clutch element on said shaft; another clutch element and a feed roller connectible with said fixed clutch element rotating on said shaft; and a device interposed between said clutch elements for engaging the same in one direction of rotation only.

22. In a feed mechanism of the class described; power transmission means having an arm to which oscillating motion is imparted; a rock shaft for said arm; fixed and loose clutch elements mounted on said shaft; means for uniting said clutch elements in one direction of rotation only; and regulating means for said power transmission means, said regulating means comprising an adjusting device whereby the radial position of said arm is varied on said shaft.

23. In a machine having working elements operating continuously; a feeding mechanism operating intermittently at regular intervals, said mechanism comprising power transmission means driving a feed roll through a clutch mounted on the same shaft as the feed roll; an independently actuatable clutch tripping device rotatably mounted with relation to said clutch; and means operable only at predetermined times of which the relative position of said working elements is the determining factor, for operating said clutch tripping device.

24. In a machine having working elements, to which blanks are fed at regular intervals; an intermittently operating feed mechanism comprising power transmission means rotating a feed roll through a clutch; an independently actuatable clutch tripping device; manually operable means for operating said clutch tripping device; and locking means for preventing operation of said manually operated means when said working elements are in predetermined positions.

25. In an intermittent feeding mechanism; power transmission means of which a clutch acting in one direction of rotation only constitutes a part; means operated manually for controlling said clutch; and means comprising a tripping device or disk rotatable by a tension member in a reverse direction to release the clutch; a member constantly bearing on said tension member to maintain said tripping device in an engaged position;

and a handle link connected to said member for lifting the same in order to effect releasing of said tension device.

26. In a machine having movable dies; an intermittent feeding mechanism; power transmission means of which a clutch acting in one direction only constitutes a part; manually operatable means for controlling said clutch, which means comprises a tripping device; a self-acting tension member for releasing said tripping device; a member bearing on and controlling said tension device; a handle or operating lever and connecting means for operating said member; and a latch for locking said handle or operating lever in predetermined positions of said movable dies.

27. In a machine having movable dies; an intermittent feeding mechanism; power transmission means of which a clutch acting in one direction only constitutes a part; manually operatable means for controlling said clutch, which means comprises a tripping device, a self-acting tension member releasing said tripping device, a movable

member bearing on and controlling said tension member, a handle and connecting means for operating said movable member; and a latch held against operation by a trip head or device actuated by said movable dies for locking said handle in predetermined positions of said movable dies.

28. In a machine having movable dies and a feeding mechanism; feed checking means; an operating lever therefor; a self-acting latch locking said lever at predetermined times; and a movable trip head capable of adjustment relatively to said dies and operated directly thereby to disengage said latch.

29. In a machine having movable dies and a feeding mechanism; feed checking means; an operating lever therefor; a pivoted latch, acting under tension, engaging and locking said lever; and a trip head movable independently of said dies but operated directly thereby at a predetermined time to disengage said latch.

In testimony whereof I have hereunto affixed my signature.

RICHARD LESTER WILCOX.
